UNITED STATES PATENT OFFICE.

CHARLES EDWARD HAVILAND, OF LIMOGES, FRANCE.

DESIGN FOR A SALAD-BOWL.

SPECIFICATION forming part of Design No. 22,618, dated July 18, 1893.

Application filed June 22, 1893. Serial No. 478,511. Term of patent 14 years.

To all whom it may concern:

Be it known that I, CHARLES EDWARD HAVILAND, a citizen of the United States, residing at the city of Limoges, in the Republic 5 of France, have invented and produced a new and original Design for a Salad-Bowl and other Articles, of which the following is a specification, reference being had to the accompanying drawings, forming part thereof, and in 10 which—

Figure 1 is a side elevation of a salad bowl bearing my design. Fig. 2 is a top view of same. Fig. 3 is a detached vertical section of same on the dotted line 3—3 of Fig. 2, and 15 Fig. 4 is a detached horizontal section of same on the dotted line 4—4 of Fig. 1.

The leading feature of my design consists of the ornamental form and configuration of the bowl, substantially as shown in the drawings.

In the drawings A designates the sides of

the bowl, which sides are inclined and composed of the corresponding scalloped sections B. Along their upper edges the sides A of the bowl are ornamented by the edge beading C, and at their lower edges forming a base is the ornamental edging composed of the beading D drawn upward at intervals, as shown at a, and the ornate surfaces E located in the spaces outlined by the beading D 30 at the points where it is drawn upward.

What I claim is—

The design for a salad-bowl and other articles, substantially as shown and described.

Signed at the city of New York, in the county 35 and State of New York, this 20th day of June, A. D. 1893.

CHARLES EDWARD HAVILAND.
